SHUTTLE TENSION

Filed June 6, 1930

Inventor,
Alexander Hannah,

By his Attorney

John R. Ward.

UNITED STATES PATENT OFFICE

ALEXANDER HANNAH, OF PATERSON, NEW JERSEY

SHUTTLE TENSION

Application filed June 6, 1930. Serial No. 459,517.

This invention relates to shuttle tension means. My object is to provide an efficient tension means which shall act to maintain proper tension and also take up slack in the thread or filling, as when the shuttle comes to a dwell in the shuttle-box after a flight, and which shall also be adapted for use in self-threading shuttles and, when so adapted, operative to impose the tension on the thread immediately, or during that pick in which the threading itself occurs.

To this end, given thread-guiding means in the shuttle, I provide a control device which is movable toward and from and normally urged in the direction from said means and which imposes a drag or frictional resistance to the pull of the thread in the opposite direction the force of which exceeds that normally urging said device in the first direction, so that when the thread is pulled in the second direction said device moves with it until it is checked, as by some positive stop, whereupon, the pull continuing, the thread slips with reference to said device, whereby the thread is tensioned; and when relaxation of the pull now occurs the second-named force then becomes active to return the device to its normal position and hence take up such slack in the thread as may exist.

When the invention is used in a self-threading shuttle the usual passage permitting entry of the thread laterally of itself into that condition where the shuttle is said to be threaded may afford the said guiding means.

35 In the drawings;

Fig. 1 is a plan of a shuttle embodying the present tension means;

Fig. 2 a side elevation thereof;

40 Fig. 3 is a longitudinal substantially central section;

Figs. 4 and 5 are sections on lines 4—4 and 5—5, Fig. 3;

Fig. 6 is a plan of the gripping device;

Fig. 7 is a transverse section thereof;

45 Fig. 8 is a longitudinal substantially central section of a shuttle embodying a modified form of the tension means;

Fig. 9 is a section on line 9—9, Fig. 8;

50 Fig. 10 is a plan of the gripping device shown in Figs. 8 and 9; and

Figs. 11 and 12 are perspective views of the clips thereof.

The shuttle body 1 has the usual cavity 2 for the wound filling or thread package 3; the shuttle shown being for silk filling 2a designates fur lining the cavity. The "eye" or thread delivery outlet 4 of the shuttle body leading from one side thereof to its cavity may be adapted to receive the thread in the example illustrated (which is a shuttle of the self-threading type) via a suitably formed longitudinal top passage 5 and a connecting transverse passage 6 which together form a longitudinally extending tongue 7 overhanging these passages, the once entered thread becoming thereby trapped; that is to say, assuming the illustrated shuttle is being used in a self-replenishing loom with means to replace a depleted package 3 with a fresh one when the shuttle is in the right-hand shuttle-box, on the ensuing flight of the shuttle to the left the thread of the fresh package, having been previously attached to the cloth, will enter passage 5 under the portion of the tongue overhanging the same and on the return or right hand flight will enter the eye via the passage 6 and become trapped in the eye, all in a well-known manner. My tension means is adapted to assume operative relation to the thread on the first (or here, the left-hand) flight of the shuttle. Of course my invention is, however, applicable where the shuttle is not of the self-threading type, but the eye 4 is threaded by hand, as with a threading hook. In any event, 4—5—6 85 may be here taken as affording the mentioned thread guiding means.

8 is a rebent strip of wire whose rebend rests on the bottom of a forward extension 2b of the cavity 2 and whose extremities are elevated and lie in a plane above the bottom and project toward the eye 4, forming a guide; the rebend is traversed by a pin 9 driven into the shuttle body and which clamps the guide 8 against the bottom of the cavity 2. Supported by the front surface of the extension 2b of cavity 2 is a spiral spring 10, which may be held in place by the extremities of the device 8 passing through its coils; there may be a plate 11, penetrated and thus 100

held in place by said extremities, against which the spring actually bears. Slidable back and forth on and lengthwise of the guideway is the thread control device, two forms of which are herein shown, the first form being constructed as follows:

A rectangular housing 12 has two opposite upright walls thereof freely penetrated by the elevated extremities of the guide 8, so that the housing is free to slide on the guide, being normally urged by spring 10 to the dotted-line position in Fig. 3. The other two opposite upright sides of the housing reach upward and form an upwardly open filling niche *b* between them and have upper and lower pairs of inturned tongues 13, the tongues in each pair having a space between them. A pair of clips 14—15 occupies these spaces and they are adapted to receive the filling *a* between them; clip 14 bears against the tongues at one side and clip 15 is urged against clip 14 by a spring 16 in the housing, so that they will clamp or grip filling *a* lying between them. The upper ends of the clips are bent off in opposite directions, forming a V-shaped crotch at 17 (Fig. 4) whereas their lower ends are bent off in the same direction (away from the spring) and lap each other, these latter ends being of such length that if the clips require to be removed this may be done by pressing them toward the spring whereupon they may be passed upward through the mentioned spaces. The left-hand or rearward edges of the clips are extended and flared at *x* to ease the slippage of the filling between them (Fig. 6).

In the modified form the housing 18 is substantially the same as the housing 12 already described excepting that the inturned tongues such as 13 are lacking and instead there are two inturned upper tangs 19; it is penetrated by and slides on the guide 8 and is subject to the rearward pressure of spring 10, as already described. The clips 20 and 21 are in this case, however, constructed so that a separate spring to produce the clamping or gripping pressure is unnecessary, thus: Clip 20 is inverted U-shaped; clip 21 is U-shaped and has the upper end of its relatively inner extremity bent outward, or over it. Each clip has in its outer extremity a hole 22 to receive one of the tangs 19. When the clips are in place in the housing, held by this engagement of the tangs in their holes 22, they exert spring pressure on each other so as to clamp or grip the filling *a* between them, and they form at 23 a V-shaped filling crotch. Their rearward edges are extended and flared (Fig. 10) to ease the slippage of the filling between them, as at *y*.

In each form a longitudinally extending filling trap 5—7 open at the (here, top) surface of the shuttle exists which is adapted to receive and trap the filling when entered laterally of itself thereto in straight taut

state, and there is a filling gripping device between this trap and the package in position to receive the intervening taut straight longitudinally extending portion of the thus-trapped filling. Thus I insure introduction of the filling into control of said device on the first pick of the shuttle after reception of a fresh package in a self-replenishing loom—a condition impossible were the gripping device positioned so low as to receive the filling only after it had reached its full-threaded position, or the level of the eye 4.

When the shuttle is in use the part of the filling *a* which is between the package 3 and filling guiding means 4 is subject to the mentioned control device which in the examples grips the filling between its clips and so maintains the tension thereon during the flight of the shuttle; that is to say, the resistance of said device to slippage of the filling relatively thereto is greater than the force represented by spring 10, wherefore on each pick said device at first shifts with the filling, compressing the spring, until said device encounters a force opposing further shifting and exceeding that of the spring as when said device has compressed the spring to its full extent, whereupon slippage of the filling relatively thereto ensues. When the pull being exerted on the filling relaxes for any reason, as when the shuttle reaches the end of its flight and slackening occurs, the force stored up in spring 10 acts to return said device and take up the slack.

If, as shown and described, the shuttle is of the self-threading type, on the first flight after introduction of a fresh package 3 the portion of the filling between said package and the point where the filling is attached to the cloth enters not only under tongue 7 but (via the crotch 17 or 23) between the clips of the control device which thus becomes immediately active on the filling in the way explained, the complete threading being accomplished on the return pick, when the filling will find its ultimate location in the eye 4. It is noted that the entrance 5 to the filling guiding means 4—5—6 opens upwardly, that is, in substantially the same direction as the crutch (17 or 23).

Having thus fully described my invention what I claim is:

1. In combination, a shuttle having a filling guiding means, and a filling control device exerting a slip-grip on the filling and guided by the shuttle for back and forth movement in a substantially straight line and toward and from said means and normally urged from the same, said slip-grip representing a force against slippage of the filling relatively to said device exceeding that of the force urging said device from said means.

2. In combination, a shuttle having a filling guiding means, and a filling clamping de-

- vice exerting a slip-grip on the filling and guided by the shuttle for back and forth movement in a substantially straight line and toward and from said means and normally urged from the same, said slip-grip representing a force against slippage of the filling relatively to said device exceeding that of the force urging said device from said means.
- 10 3. In combination, a shuttle having a filling guiding means, a filling control device exerting a slip-grip on the filling and guided by the shuttle for back and forth movement in a substantially straight line and toward and from said means, and a spring opposing movement of said device toward said means and representing a force less than said slip-grip to slippage of the filling relatively to said device.
- 15 4. In combination, a shuttle body having a filling guiding means, a guide arranged in said body and extending toward said means, a filling control device exerting a slip-grip on the filling and having spaced portions penetrated by and said device being movable along the guide back and forth, and a spring opposing movement of said device toward said means.
- 20 5. In combination, a shuttle body having a filling guiding means, a guide arranged in said body and extending toward said means, a filling control device exerting a slip-grip on the filling and movable on the guide back and forth, and a spiral spring opposing movement of said device toward said means and penetrated by the guide.
- 25 6. In combination, a shuttle having a filling guiding means formed to receive the filling laterally of itself and a filling control device exerting a slip-grip on the filling and confined by the shuttle to back and forth movement and normally urged in one direction and formed to receive the filling laterally of itself from substantially the same direction as the filling is admitted to said guiding means and having its slip-grip representing a force against slippage of the filling relatively to said device exceeding that of the force urging said device in said direction.
- 30 7. In combination, a shuttle having a filling guiding means formed to receive the filling laterally of itself and a filling control device exerting a slip-grip on the filling and guided by the shuttle for back and forth movement toward and from said means and normally urged from the same and formed to receive the filling laterally of itself from substantially the same direction as the filling is admitted to said guiding means and having its slip-grip representing a force against slippage of the filling relatively to said device exceeding that of the force urging said device from said means.
- 35 8. In combination, a shuttle having a filling guiding means formed to receive the filling laterally of itself and a filling control device exerting a slip-grip on the filling and guided by the shuttle for back and forth movement in a substantially straight line toward and from said means and normally urged from the same and formed to receive the filling laterally of itself from substantially the same direction as the filling is admitted to said guiding means and having its slip-grip representing a force against slippage of the filling relatively to said device exceeding that of the force urging said device from said means.
- 40 9. In combination, a shuttle, a filling package therein, said shuttle having a filling guiding means formed to receive the filling laterally of itself and while extending substantially straight and longitudinally of the shuttle when in flight, and a filling gripping means arranged between said package and guiding means and confined by the shuttle to back and forth movement lengthwise thereof and normally urged toward said package and also formed to receive the filling laterally of itself, the grip of said gripping means on the filling representing a force against slippage of the filling relatively to the guiding means exceeding that of the force urging said means toward the package.
